FOLDING LIGHT AUTOMATIC RIFLE

Alonzo F. Gaidos, Redwood City, Calif.

Application February 1, 1950, Serial No. 141,801

4 Claims. (Cl. 42—75)

(Granted under Title 35, U. S. Code (1952),
sec. 266)

1

This invention relates to a small light weight automatic firearm.

An object of this invention is to provide an easily transported firearm which can be stowed in a small pack or similar carrier.

A particular object of this invention is to provide a firearm which can be disassembled into small units and then stowed in a small pack which can be readily carried on the back of a paratrooper or the like.

Another object of this invention is to provide a firearm which can be quickly disassembled into a small number of units or assembled in the optimum of time without the use of tools.

Another object of this invention is to provide a light weight firearm which can be fired semi-automatically or automatically.

Another object of this invention is to provide a firearm having a simple safety mechanism which is easily operated.

Another object of this invention is to provide a firearm with an improved means for locking the bolt in the battery position.

Another object of this invention is to provide a firearm which may be readily assembled or disassembled with a minimum number of tools.

The specific nature of the invention as well as other objects and advantages thereof will clearly appear from a description of a preferred embodiment as shown in the accompanying drawings in which:

Fig. 1 is a longitudinal cross sectional view of the receiver and bolt with the striker in the cocked position.

Fig. 2 is a longitudinal view partly in section of a portion of the barrel assembly and is identified to be read as though attached to the right-hand edge of Fig. 1.

Fig. 3 is a longitudinal view partly in section of the muzzle end of the barrel and is a continuation of Fig. 2.

Fig. 4 is a longitudinal view of the three units comprising this invention disassembled.

Fig. 5 is a perspective view of the actuator bar.

Fig. 6 is a view similar to Fig. 1 but in the fired position.

Fig. 7 is an enlarged plan view of the bolt return spring rod assembly.

Fig. 8 is an enlarged cross sectional view taken on line 8—8 of Fig. 1.

Fig. 9 is a right side enlarged view of the automatic sear.

Fig. 10 is a cross sectional view taken on line 10—10 of Fig. 6.

2

Fig. 11 is a view similar to Fig. 1 showing the bolt in the recoiled position.

Fig. 12 is a cross sectional view taken on line 12—12 of Fig. 11.

Fig. 13 is a cross sectional view taken on line 13—13 of Fig. 1.

Fig. 14 is an enlarged side view of the ejector.

Fig. 15 is an enlarged side view of the extractor.

Fig. 16 is a partial longitudinal cross sectional view of the firing mechanism in the full automatic position.

Fig. 17 is an enlarged cross sectional view taken on line 17—17 of Fig. 13.

Fig. 18 is a right side enlarged view of the semiautomatic sear.

Fig. 19 is an enlarged partial longitudinal cross sectional view of the hinge portions.

The gun disclosed in this invention comprises primarily three units for ease of transportation, particularly a stock assembly 12, a receiver assembly 13 which is hinged thereto, and a barrel assembly 14 which is best shown in Fig. 4.

Stock assembly 12 comprises a shoulder stock 15, a stock hinge 16, stock hinge screws 17 and a connector rod assembly 18. The connector rod assembly 18 comprises a rod 19, a knob 20 and a pin 21 for fastening the knob 20 on rod 19. The rear end of stock 15 is provided with a conventional butt plate 129.

Receiver assembly 13 comprises a housing or intermediate stock portion 22, a receiver 23 and a trigger guard 24. Receiver housing 22 is formed as an extension of shoulder stock 15 and is provided with an anchor plate 25 on the rear end thereof which is fastened thereto by screws 26, anchor plate 25 being provided with a threaded hole 27 to receive a threaded end 103 of connector rod 19 (Fig. 19).

Receiver 23 is provided with a threaded longitudinal recess 28 in the upper rear end thereof to receive a striker retainer 29. The forward end of receiver 23 has a longitudinal protruding cylindrical boss 30 with exterior threads 31 provided for a purpose which will be explained later. Receiver 23 is provided with a dovetail transverse slot 226 to receive a conventional rear sight 227.

A longitudinal bore 32 is provided in the upper forward part of receiver 23 extending out through boss 30 to receive a bolt assembly 33. Receiver 23 has a downward depending rectangular portion 34 being provided with a vertical magazine opening 35 and an angular slot 36 to receive a lock 37 which will be later described.

Extending forwardly from threaded recess 28 a longitudinal bore 38 is provided to receive a striker 39. Forwardly of longitudinal bore 38 a small bore 40 is provided to slidably support a reduced end 41 on striker 39. Forwardly of bore 40 and connected to bore 32 an enlarged bore 42 is provided to receive a buffer 43. On the forward upper right side of receiver 23 angularly disposed is a slot 44 to permit ejection of a fired round, and for the accommodation of a bolt handle 80. On the rear surface of portion 34 a transverse slot 242 is provided to receive a retainer 45 of a bolt return spring rod 46.

Depending from the lower rear end of receiver 23 a rectangular projection 47 is provided to receive a trigger retaining clamp 48. Projection 47 is provided with a vertical cylindrical recess 49 to receive clamp 48. Centrally disposed in recess 49 a threaded hole 50 is provided to receive a trigger guard screw 51. Forwardly of projection 47 a depending lug 52 is provided with a transverse slot 53 to receive a retainer 54 of rod 46. A helical spring 71 surrounds bolt return spring rod 46 for a purpose to be later described. A pair of longitudinally disposed holes 55 is provided in projection 47 to receive sear return plunger 56. A transverse hole 57 is provided approximately at the rear of receiver 23 below bore 38 and at right angles therewith to receive a safety lever 58. Forwardly of hole 57 and in line therewith a transverse hole 59 is provided to receive a sear pin 60. Sear pin 60 is provided to receive an automatic sear 61 and a semi-automatic sear 62, such sears being pivotally mounted thereon. Forwardly of hole 59 another transverse hole 63 is provided to receive a stop pin 64 which limits the counterclockwise movement of sear 62.

Striker 39 comprises an enlarged diametrical rear end 65 having an angular projection 66 on the bottom end thereof forming a hook for the engagement of the sears. A cylindrical recess 67 is provided in the rear end of striker 39 to receive the forward end of a striker spring 68. Striker retainer 29 is provided with a cylindrical bore 69 oppositely disposed to recess 67 to receive the rear end of striker spring 68. Striker retainer 29 is provided with a knurled cylindrical head 70 to permit such retainer to be assembled in threaded recess 28.

A bolt 72 cylindrical in contour is provided with a longitudinal bore 73 therein to receive a firing pin 74 of a conventional shape and such bolt is reciprocable in bore 32. A firing pin spring 232 surrounds pin 74 thereby biasing such pin rearwardly. Bolt 72 is provided on the rear end thereof with vertically positioned ways 75 to receive a firing pin retainer 76. Firing pin 74 has a reduced diametrical portion 77 on the rear end thereof which is slidably received in a hole 78 of retainer 76. Bolt 72 is provided with a longitudinal dovetailed slot 79 on the forward right side angularly disposed above the horizontal axis thereof to receive bolt handle 80. A longitudinal slot 81 with a semi-cylindrical bottom is provided oppositely opposed to slot 79 on the left side of bolt 72 in the forward end thereof to slidably receive an ejector 82.

Bolt 72 is provided with a longitudinal shallow slot 234 rearwardly of and aligned with slot 79 therein to receive a bolt handle strap 228. Strap 228 is provided with a protruding stud 243 which nests in a detent 244 thereby retaining bolt handle 80 in position. Rearwardly of and in line with a slot 81 there is provided an ejector

stop clearance longitudinal slot 235 to permit the free movement of bolt 72 in bore 32 of receiver 23. In the forward part of slot 81 there is provided a raised square lug 236 to limit the 5 rearward movement of ejector 82. Ejector 82 has an elongated longitudinal notch 237 arranged for slidable engagement over lug 236 in slot 81. Ejector 82 is urged rearwardly by an ejector spring 238 which is assembled in slot 81 between a rear surface 239 of lug 236 and a rear surface 240 of notch 237. When the bolt assembly 33 moves rearwardly in recoil after discharging cartridge 131, ejector 82 comes in contact with an ejector stop 241 secured to receiver 23 and protruding into bore 32 whereby ejector 82 stops in relation to the bolt thereby ejecting spent cartridge 131 out of the receiver 23 through slot 44. Bolt 72 is provided with a transverse slot 83 on the bottom near the rear end to receive 20 lock 37.

Bolt handle 80 has a depending arcuate handle portion 84 for manually operating bolt 72. A longitudinal rectangular slot 85 is provided on bolt handle 80 to receive a spring biased extractor 86 which is pivotally secured thereto by an extractor pin 87. Retainer 76 is provided with a rectangular open slot 88 on the bottom end thereof to permit a bolt return slide 89 to contact bolt 72. Bolt return slide 89 is provided with a 25 depending body portion 90 having an axial hole 91 therein. Bolt return slide 89 is slidably mounted on bolt return spring stud 46 by means of hole 91. Bolt return slide 89 is biased forwardly by bolt return spring 71 thereby urging bolt 72 into the battery position. Lock 37 is provided with a rectangular open slot 92 angularly disposed on the left side thereof for a purpose to be later described.

Trigger guard 24 is provided with a rear hinge 40 portion 93 terminating in a depending boss 94 having a transverse hole 95 therethrough. Shoulder stock 15 is pivotally mounted to receiver housing 22 by a hinge screw 96 which passes through hole 95 of boss 94 and is threadably secured to stock hinge 16. A vertical counterbored hole 97 is provided near the rear end to receive screw 51. A longitudinal rectangular recess 98 terminating in semi-cylindrical ends 99 is provided on the top of trigger guard 24 to receive 45 a trigger retainer 100. A vertical threaded hole 101 is provided on the forward part of recess 98 to receive a trigger retainer screw 102.

Trigger retainer 100 is held in position at the rear end by retainer clamp 48. An elongated 50 longitudinal slot 104 opening from the rear end is provided in trigger retainer 100 to permit a trigger 105 to slidably pass therethrough. Trigger 105 is provided with the conventional type finger piece 106 depending therefrom. A cylindrical longitudinal recess 107 is provided in the rear end of trigger 105 to receive a spring biased trigger return plunger 108 to urge such trigger forwardly. Opposed longitudinal rectangular slots 109 are provided to slidably mount trigger 65 105 on retainer 100. A rectangular longitudinal seat 110 opening on the top and right side of trigger 105 is provided to receive trigger latch body 111 which is welded thereto or can be made integral therewith. A transverse cylindrical recess 112 is provided on the rear right side of trigger 105 to receive an automatic lever pin 113 for the pivotal mounting of an automatic lever 114.

Trigger latch body 111 is provided with a transverse hole 115 in the center thereof to receive 75

a trigger latch 116. A transverse raised projection 117 is provided on the rear end of body 111 with a forwardly opening slot 118 to receive a flat trigger latch spring 119 which biases trigger latch 116 clockwise. Automatic lever 114 has a transverse hole 120 for mounting such lever on pin 113. Automatic lever 114 is provided with an upstanding arm 121 for the functioning of the semi-automatic sear 62 and a downwardly projecting arm 122 for limiting the pivotal movement of lever 114 in the automatic position.

Automatic sear 61 is provided with a transverse hole 124 for pivotally mounting such sear on sear pin 60. An upstanding projection 125 is provided on the forward top portion of automatic sear 61 for the engagement of projection 66 on striker 39. On the lower left hand side of automatic sear 61 a transverse projecting lug 126 is provided for engagement with latch 116. Semi-automatic sear 62 is constructed similar to automatic sear 61 with the exception that a ledge 127 is provided on the front end thereof for engagement with pin 64 and a lower transverse projecting lug 128 being on the right side similar to lug 126 of sear 61 but oppositely disposed. Semiautomatic sear 62 is also provided with a projection 123 on the rear end arcuately formed for engagement with safety lever 58.

A conventional magazine 130 constructed to receive a double row of cartridges 131 is used with this invention and is removably retained in magazine opening 35 of depending portion 34 by a resilient latch 132 which is pivotally secured to the lower front surface of receiver 23. Latch 132 has a rearwardly projecting horizontal ledge 133 which engages a slot 134 in magazine 130 to position such magazine in the operative position.

Barrel assembly 14 comprises a barrel 135, a barrel nut 136, an actuator assembly 137 and a forestock assembly 138. The rear end of barrel 135 is of reduced diameter as shown at 139 to slidably fit in bore 32 of receiver 23. Forwardly of end 139 an enlarged diameter portion 140 is provided to be rotatably received in a counterbore 141 of nut 136. The rear end of counterbore 141 in barrel nut 136 is interiorly threaded as shown at 145 to engage with threads 31 and thereby secure barrel 135 in receiver 23. The rear portion of the enlarged diameter 140 is provided with a longitudinal keyway 142 on the top and bottom to receive a pair of keys 143 which are also receivable in slots 144 in boss 30 of receiver 23 to properly align and position the barrel in the receiver and also to prevent rotation of barrel 135 and prevent upsetting the headspace. Forwardly of enlarged diameter 140, barrel 135 is provided with annular ribs 146 equidistant apart and extending approximately one-half the length of the barrel to effect the cooling of the barrel. Forwardly of ribs 146 barrel 135 is provided with a reduced diameter portion 147 to receive a rear barrel band 148. Portion 147 is provided with a longitudinal keyway 149 on the top surface thereof which is in alignment with keyway 142. The muzzle end of barrel 135 is a reduced portion 150 to slidably receive an actuator 151. Rearwardly of portion 150 a threaded diameter 152 is provided to receive a front barrel band retaining nut 153. An enlarged diameter 154 rearwardly of threads 152 is provided to receive a front barrel band 155. Diameter 154 has a keyway 156 provided on the top which is in longitudinal alignment with keyways 142 and 149.

Rear barrel band 148 is provided with a longitudinal bore 157 to receive portion 147 of barrel 135. A longitudinal keyway 158 is provided on the top part of bore 157 to receive a key 159. Vertically below bore 157 and in alignment therewith a counterbore 160 is provided to receive the rear end of an actuator spring housing 161. Rearwardly of counterbore 160 a reduced diameter hole 162 is provided to slidably receive an actuator rod 163. Bifurcated downwardly depending ears 164 are provided at the bottom of rear barrel band 148 to receive eye bolt 165 therebetween. Ears 164 are provided with suitable transverse holes 166 to threadably secure an eye bolt screw 167 which passes freely through the eye in bolt 165 to permit pivotal movement of forestock 138 about screw 167 in rear barrel band 148.

Front barrel band 155 is provided with a longitudinal bore 168 to receive diameter 154 of barrel 135. A keyway 169 is provided on the top part of bore 168 to receive a key 170 for securing such band on barrel 135. Vertically above and transverse therewith front band 155 is provided with a dovetailed slot 171 to receive a front sight 172. Vertically below bore 168 and opposing counterbore 160 of rear band 148 front band 155 is provided with a counterbore 173 to receive the forward end of actuator spring housing 161. Forwardly of counterbore 173 a small diameter hole 174 is provided to slidably receive an actuator rod extension 187. Front barrel band retaining nut 153 is provided with a longitudinal threaded bore 175 for threadable engagement with threaded diameter 152 of barrel 135 thereby securely positioning front band 155.

Actuator 151 is provided with a longitudinal bore 176 at the front end thereof to permit passage of a fired bullet 177. A bore 178 is provided in the rear end of actuator 151 and is slidably receivable on portion 150 of barrel 135. A gas chamber 179 is provided between bores 176 and 178 to permit the expansion of the gases and also the impinging of same on the forward inside wall 180 of actuator 151. Downwardly depending from actuator 151 there is provided a lug 181 having a longitudinal bore 182 therein to receive an actuator rod nut 183. Bore 182 is provided with a transverse hole 184 to receive a lock pin 185 for securing nut 183 in position. Nut 183 is provided with a knurled head 186 to facilitate assembly. Nut 183 is provided with a longitudinal cylindrical recess 188 in the rear end thereof and a threaded recess 189 forwardly therefrom to receive a threaded end 190 of extension 187. Actuator spring housing 161 is provided with a longitudinal counterbore 191 on each end thereof for a purpose to be later described.

A thin vertical wall section 192 is provided in actuator spring housing 161 between counterbores 191 and having a longitudinal small hole 193 to slidably receive extension 187. An enlarged diameter portion 194 is provided on the rear end of extension 187 and is slidably received in the rear counterbore 191 of housing 161. Enlarged portion 194 is provided with a longitudinal threaded recess 195 therein to threadably secure a threaded end 196 of rod 163. Forwardly of enlarged portion 194 an intermediate reduced diameter portion 197 is provided to be slidably received in hole 193 of housing 161. The forward end of extension 187 is a reduced diameter portion 198 and is slidably received in hole 174 of barrel band 155. A shoulder 199 is formed at

the intersection of portions 197 and 198 providing a stopping surface for a washer 200.

An actuating spring 201 is assembled in the forward counterbore of housing 161 between the bottom surface of counterbore 173 of front band 155 and against washer 200 to bias actuating rod extension 187 rearwardly. An actuator rod buffer 202 is slidably mounted in the rear counterbore of housing 161 to slidably receive portion 197 of extension 187 to absorb the shock when the large portion 194 goes forwardly under the impact of the actuating gases. The rearward end of actuator rod 163 has an annular recess 203 to receive a stepped notch 204 of an actuator bar 205 which is loosely coupled therein (Fig. 5).

Actuator bar 205 is provided with an offset lug 206 facing to the right and on the front end to accommodate notch 204. A lock actuating stud 207 is provided in the center and protrudes to the right of actuator bar 205 for a purpose to be described later. An offset projection 208 protruding to the right on the rear end is provided on actuator bar 205 for a purpose to be later described.

Forestock assembly 138 comprises a forestock 209 which is approximately rectangular in cross-section and is arcuately relieved on the top portion to receive barrel 135. A latch housing retainer 210 is secured to the rear end of stock 209 by conventional wood screws. Latch housing retainer 210 is provided with a longitudinal hole 211 to receive a latch bar 212 for locking forestock assembly 138 to the firearm through the means of a latch plate 213 which is secured to receiver housing 22 on the front end thereof by conventional wood screws.

A longitudinal recess 214 axially aligned with hole 211 in forestock 209 is provided to receive a latch housing 215. Latch housing 215 is provided with a longitudinal recess 216 to receive latch bar 212. A helical spring 217 is provided to bias latch bar 212 rearwardly in latch housing 215. Latch bar 212 is provided with a vertical threaded recess 218 to receive a latch screw 219. Latch housing 215 is provided with a longitudinal slot 220 in the bottom side thereof to permit passage therethrough of latch screw 219. An enlarged knurled head 221 is provided on latch screw 219 and extends through the bottom of forestock 209 to permit the manual forward release of latch bar 212 thereby allowing the forestock assembly 138 to be pivoted downwardly through the means of eye bolt 165 which is threadably secured in the forward part of forestock 209.

Forestock 209 is provided with a rectangular longitudinal slot 222 opening from the top on the rear end thereof to receive a barrel nut lock 223 which is secured to the bottom surface thereof. Barrel nut lock 223 is provided with a resilient upstanding tooth 224 which cooperates with longitudinal serrations 225 on barrel nut 136 whereby such nut secures barrel 135 at the proper headspace in relation to bolt 72, and secures such barrel to receiver 23. A narrow longitudinal slot 233 is provided forwardly of slot 222 in forestock 209 to accommodate rod 163.

To disassemble the barrel assembly 14 for stowing purposes, as shown in Figs. 2 and 4, it is only necessary to first pull latch screw 219 forwardly thereby removing latch bar 212 out of engagement with latch plate 213 of receiver housing 22 whereby forestock assembly 138 can be swung downwardly; second, disconnect actuator rod 163 from notch 204 of actuator bar 205; and

third, unscrew barrel nut 136 forwardly from out of engagement with thread 31 of receiver 23. The hinging of the stock assembly 12 in relation to the receiver assembly 13, as shown in Fig. 4, 5 can be accomplished simply by unscrewing connector rod assembly 18 rearwardly from anchor plate 25 of receiver housing 22.

Bolt 72 can be removed from the receiver assembly 13 after the barrel assembly 14 is detached 10 therefrom by first removing bolt handle strap 228 which resiliently holds bolt handle 80 secured in bolt 72; second, depressing lock 37 out of engagement with slot 83 in bolt 72 which may be accomplished either by pulling actuator bar 205 15 forwardly which protrudes out of the front of receiver assembly 13, or by pushing forwardly manually operated bolt release lever 229 which protrudes through a slot 230 in the left side of the rifle and is secured to actuator bar 205; third, 20 retract bolt 72 rearwardly sufficiently to remove handle 80 out of slot 44 of receiver 23; and fourth, release striker 39 and under the bias of striker spring 68, bolt 72 will be forced forwardly clear of the receiver assembly 13.

Operation

After the insertion of the magazine 130 loaded 25 with the cartridges 131 into the magazine opening 35 of receiver 23 and secured therein by magazine latch 132, lock 37 is angularly cammed 30 downwardly out of slot 83 of bolt 72 by pressing forwardly lever 229 with the thumb of the left hand, such lever being on the left side of the rifle. The bolt 72 is then retracted to the rear by 35 handle 80 permitting the uppermost round 131 in the magazine 130 to enter the chambering space between the bolt 72 and the end of the barrel 135 whereby on the return of the bolt into the battery position, the round is chambered 40 in the barrel and the gun is charged for firing. Before firing, the safety lever 58 must be set in the "fire" position.

Semiautomatic and automatic fire are both accomplished by pulling the trigger 105 rearwardly 45 in a horizontal plane varying distances, that is, pulling the trigger only part way operates the gun in semiautomatic fire and pulling it all the way until it stops, operates the gun in automatic fire. When the trigger 105 is pulled rearwardly 50 the spring biased latch 116 pivotally attached thereto, trips the automatic and semiautomatic sears 61 and 62, respectively, thereby releasing the striker 39 allowing same to go forwardly under the urging of striker spring 68, striking 55 firing pin 74 in bolt 72 thereby discharging cartridge 131. As the bullet 177 travels along the bore 231, the bolt is locked. When the bullet 177 has cleared the bore 231 at the muzzle end and while passing through gas chamber 179 in 60 the actuator 151, the gases escaping from the bore 231 impinge on the front wall 180 thereby forcing the actuator 151 forwardly which in turn moves the actuator bar 205 also forwardly thereby camming the lock 37 downwardly. With the assistance of the back pressure of the gases developed 65 at the instant bullet 177 is passing through bullet aperture 176 of expansion chamber 179 of actuator 151, bolt 72 is driven rearwardly and the spring pressed striker is then returned rearwardly 70 and is engaged by the automatic and semiautomatic sears. At the end of the recoil stroke the bolt 72 is returned to the battery position under the bias of spring 71, picking up the uppermost cartridge 131 from the magazine 130 75 and chambering same in the barrel. Scavenging

of remaining gases in chamber 179 is accomplished by vacuum formed by the base of bullet 177 as it leaves aperture 176. The actuator bar 205 is returned rearwardly under the bias of spring 201 thereby camming the lock upwardly and locking the bolt in the battery position.

In automatic fire when the trigger 105 is pulled to the stop position, the automatic lever 114 holds the semiautomatic sear 62 only rearwardly preventing its engagement with striker projection 66. When the semiautomatic sear is thus held out of engagement, the automatic sear 64 functions normally and is released from the striker 39 by the projection 208 of actuator bar 205 after the actuator 151 returns to the normal position under the bias of spring 201 thereby continuing the firing until the trigger is released. In semi-automatic fire when trigger 105 is pulled rearwardly and the latch 116 disconnects both the sears, such latch then overrides the bottom portions 126 and 128 of automatic and semiautomatic sears, respectively, under the bias of plungers 56 thereby allowing the sears to re-engage the striker 39 and the trigger 105 then has to be returned to its forward position before latch 116 can re-engage the sears.

It will therefore be apparent to one skilled in the art that application of the principle of the invention disclosed herein provides novel and improved firearm construction which is outstandingly characterized by a small number of parts and simplicity of configuration of such parts. In addition, a light weight rifle is disclosed which can quickly and without the aid of tools be disassembled in three small units for convenience in transportation of such light rifle.

I claim:

1. In an automatic firearm having a hinged stock unit and a receiver unit, the combination of, a barrel unit comprising a barrel, a sleeve releasably coupling said barrel to the receiver unit in longitudinal alignment, a barrel band fixedly secured to said barrel, a forestock pivotally secured to said barrel band, latching means to releasably secure said forestock to the receiver unit in longitudinal alignment, and a lock located in the bottom of a longitudinal recess in said forestock under said sleeve and provided with an upstanding portion terminating in an apex top portion to cooperate with longitudinal serrations on said sleeve whereby rotation of said sleeve is prevented when said barrel unit and said forestock are in longitudinal alignment with the receiver unit and whereby said lock cannot be disengaged from said serrations when said forestock is in longitudinal alignment with said barrel unit.

2. In a firearm having a receiver, a barrel removably coupled thereto, and a trigger guard secured to the underside of the receiver, the combination of an intermediate stock portion forming a seat for the receiver and having an opening in the underside thereof for passage of the trigger guard therethrough, a strip-like extension projecting rearwardly from the trigger guard in abutment with the underside of said intermediate stock portion, a shoulder stock portion hingedly secured to the terminal end of said trigger guard extension for pivotal movement between an extended position forming a continuation of said intermediate portion and a stowed position wherein said shoulder portion is folded forwardly beneath said intermediate portion, means for locking said shoulder stock portion in

the extended position thereof, a forestock portion mounted to the underside of the barrel forwardly of said intermediate stock portion, and releasable latch means for locking said forestock portion to said intermediate stock portion in longitudinal alignment therewith.

3. In a firearm, the combination of a receiver, a bolt slidably mounted in said receiver for longitudinal reciprocal movement, a barrel having a depending front band thereon, a sleeve coupling said barrel to said receiver in the proper headspace relationship relative to said bolt, key means for preventing relative rotation between said barrel and said receiver, an intermediate stock portion forming a seat for said receiver and substantially coextensive therewith, a shoulder stock portion hingedly secured to said intermediate stock portion for pivotal movement between an extended position forming a continuation of said intermediate portion and a stowed position wherein said shoulder portion is folded forwardly beneath said intermediate portion, screw means releasably locking said shoulder stock portion to said intermediate portion in said extended position of said shoulder portion, a forestock portion pivotally mounted at the front end thereof to said barrel band, latch means in the rear end of said forestock portion engageable with the front end of said intermediate portion to hold said forestock portion in longitudinal alignment therewith, said barrel coupling sleeve having a plurality of annularly disposed serrations on the exterior thereof, an upwardly projecting detent in said forestock engageable in one of said serrations for locking said coupling sleeve against rotation and thereby preventing any change in the headspace relationship between said bolt and said barrel, and means for releasing said latch means to disengage said forestock portion from said intermediate stock portion whereby said forestock portion is free to pivot about the front end thereof and thereby withdraw said detent from locking engagement in one of said serrations in said sleeve to permit uncoupling of said barrel from said receiver.

4. In a firearm having a receiver and a barrel removably coupled thereto, the combination of an intermediate stock portion forming a seat for the receiver and substantially coextensive therewith, a shoulder stock portion hingedly secured to the rear end of said intermediate stock portion for pivotal movement between an extended position wherein said shoulder portion forms a continuation of said intermediate portion and a stowed position wherein said shoulder portion is folded forwardly beneath said intermediate portion, means for locking said shoulder portion in the extended position thereof, a forestock portion having a screw secured in the front end thereof and projecting forwardly therefrom to terminate in an eye portion, a depending front band on the barrel, key means for locking said front band against rotation relative to said barrel, said front band having a bifurcated portion on the underside thereof for rotatably receiving said eye portion of said screw therebetween, a bolt threadably secured in said front band bifurcated portion and passing through said eye portion whereby said forestock portion is pivotally secured to said front barrel band, and releasable latch means for locking said forestock portion to the front end of said intermediate stock portion in longitudinal alignment therewith.
